UNITED STATES PATENT OFFICE.

WALTER HAGENBUCH, OF MARTINEZ, CALIFORNIA, ASSIGNOR TO SHELL COMPANY OF CALIFORNIA, A CORPORATION OF CALIFORNIA.

WHARF.

1,300,606.

Specification of Letters Patent. Patented Apr. 15, 1919.

Application filed June 10, 1918. Serial No. 239,318.

To all whom it may concern:

Be it known that I, WALTER HAGENBUCH, a citizen of the United States, residing at Martinez, in the county of Contra Costa 5 and State of California, have invented a new and useful Wharf, of which the following is a specification.

My invention relates to wharf construction, being more particularly a shock absorber or fore-construction for wharves. In order to increase the life of a wharf it is desirable to build an independent forestructure which is able to absorb the impact of landing vessels without transmitting this 15 impact to the main body of the wharf. It is essential that this forestructure be flexible enough to receive a normal impact without injury either to itself or the landing vessel. These requirements are the better fulfilled 20 the bigger the allowable movement and the bigger the ultimate horizontal load the forestructure is able to resist. It has been common practice to use vertical piles supported horizontally by solid connected brace piles, 25 and this construction may withstand a big load, but it cannot absorb much of the energy stored in the moving vessel because it is only able to move a very short distance without the brace piles or the connection 30 between the brace piles and vertical piles being overstressed and destroyed. Vertical piles in two rows arranged in staggered relation to each other are commonly used for ferry slips and like construction. 35 This construction will allow considerable movement, but the horizontal load at normal bending stress of the piles is relatively small, compared to the number of piles used.

With my construction I propose to use a 40 forestructure consisting of a series of vertical piles spaced apart from the main structure of the wharf, the vertical piles being connected by horizontally arranged timbers, the vertical piles having connected thereto, 45 in slidable relation, brace piles diagonally arranged with respect to the vertical piles and elastic means for governing the relation of the vertical piles with the associated brace piles. Such construction destroys a 50 very large number of foot pounds more energy than either of the constructions above referred to, assuming the piles are stressed the same amount.

Other objects and advantages will appear 55 hereinafter from the following description.

Referring to the drawings, which are for illustrative purposes only,

Figure 1 is a plan view of a portion of a wharf embodying a form of my invention.

Fig. 2 is a vertical sectional view on line 60 2-2, Fig. 1.

Fig. 3 is a vertical sectional view on line 3-3, Fig. 1.

Fig. 4 is an enlarged vertical sectional view of a portion of the wharf shown in 65 Fig. 2.

Fig. 5 is a face view of a vertical pile shown in Fig. 4, the brace pile being omitted.

Fig. 6 is a horizontal sectional view on line 6-6, Fig. 4.

11 designates the wharf proper supported on suitable vertical piles 12, braced by means of suitable timbers 13, and 14 designates in general the shock absorber or fore-structure of the wharf proper. This shock 70 absorber consists of a series of vertical piles 16 spaced apart and independent from the wharf proper 11 and is arranged on both sides of the wharf as shown in Figs. 1 and 2. The vertical piles 16 are connected together by means of horizontally disposed timbers 17 secured to the vertical piles 16 by means of suitable bolts 18. Arranged in association with each vertical pile 16 is a brace pile 20 diagonally disposed and ex- 75 tending downwardly and inwardly from its upper end, the upper end of the brace pile being cut away as indicated at 21 in Fig. 6 to form a saddle which engages a portion of the inner face of the vertical pile 16. 22 80 designates horizontally disposed timbers which connect the brace piles 20, bolts 23 being used for this purpose which extend through the timbers 22 and brace piles 20. 24 designates horizontally disposed head 85 timbers which are seated upon the top of the brace piles, connected thereto by drift bolts 25.

Each vertical pile 16 has secured to its inner face by means of bolts 26 a plate or bracket 27, the upper end of which forms an eye 28 for receiving the lower end 29 of a U shaped tie rod 30. The two legs 31 of the rod 30 extend upwardly through openings 32 formed in the timbers 24. Confined between plates 33 and 34 on the upper ends of the rod 30 are coiled springs 35 and 36, being separated by a spacing plate 37, the plate 37 being for the purpose of preventing buckling and smashing of the coils. 38 designates 100 105 110

5 nuts on the upper ends of the rod 30 by means of which the springs are confined between the plate 33 and the plate 34, the plate 34 being seated on the upper face of the timbers 24 above referred to.

10 Each vertical pile 16 is also connected to its associated brace pile 20 by means of a chain 40, which, in the form shown, has one end connected to one of the bolts 26 and the other end connected to one of the bolts 23, which chain serves to keep the vertical pile in its vertical position when not horizontally loaded, that is, the chain keeps the vertical pile from leaning outwardly and 15 limits the forward movement caused by the initial compression of the spring. 42 designates a buffer, of any common form of construction, arranged horizontally along the outside of the vertical piles 16, being supported thereon in any suitable manner, as by a chain indicated at 43.

20 It is to be understood that similar brace piles may be used on the wharf proper construction as shown in Fig. 2 at 50, if so desired.

25 When the vertical piles 16 receive an impact due to a vessel landing against the buffers 42 the movement of the upper ends of the vertical piles inwardly causes a compression of the springs 35 and 36 which takes place due to the relative movement between the vertical piles and the brace piles, the brace piles and the timbers 24 thereon sliding on the inner faces of the vertical piles 30 which action shortens the distance between the timbers 24 and the plates 33 thereby compressing the springs and taking up the load. In the event the load or impact is suddenly removed, as when a vessel quickly moves 35 away from contact with the buffers 42, the chains 40 prevent the vertical piles 16 from snapping away from their associated brace piles.

40 The springs 35 and 36 are preferably of the type known as standard car springs and are arranged vertically or nearly so, the advantage of this being that the vertical springs, for the same amount of deflection of the springs would allow about double the 45 horizontal deflection of the piles as compared to any other arrangement of the spring. Another advantage of arranging the springs as shown is that the brace piles do not necessarily have to be parallel with each other. 50 In other words, the direction of the brace piles as well as the direction of the horizontal movement may vary over a considerable angle which would not be true in using horizontally arranged springs because the 55 movement in such case has to be in the direction of the axis of the spring, and the latter have to be parallel to each other. In using vertically arranged springs the movement of the springs is vertical regardless of the horizontal direction of the movement.

60 It is also to be noted that only one end of the springs is rigidly connected to the structure, the other end being free to move horizontally with relation to the connected end. This is important because it avoids lateral displacement which occurs when both ends of the spring are connected to a structure, when one end has a tendency to move at an angle to the axis of the springs.

65 What I claim is:

1. In a wharf structure, a vertically arranged pile, a diagonally arranged brace pile for said vertical pile, said brace pile having its upper end in sliding relation to the vertical pile, and elastic means for holding 80 the vertical pile in such relation to the brace pile.

2. In a wharf, a fore-structure comprising a series of vertically arranged piles, means for connecting said piles together, 85 brace piles coacting with the vertical piles having their upper end in sliding relation with their associated vertical piles, compression springs on the brace piles, and means on the vertical piles for engaging said 90 springs to compress the springs by movement of the vertical piles.

3. In a wharf, a fore-structure comprising a series of vertically arranged piles, brace piles coacting with the vertical piles 95 each having their upper end in sliding engagement with its associated vertical pile, vertically disposed coiled springs on the upper end of each brace pile, and means on the vertical piles engaging said springs to compress the springs by movement of the vertical piles.

4. In a wharf, a fore-structure comprising a series of vertical piles, timbers connecting said piles, brace piles coacting with the vertical piles having their upper ends in sliding engagement with the vertical piles, head timbers on the upper end of said brace piles connecting said brace piles together, coiled springs vertically arranged on said head 110 timbers, a plate on the upper end of said springs, and rods secured to said vertical piles engaging said plate to compress said springs by movement of the vertical piles.

5. In a wharf, a fore-structure comprising a series of vertical piles, timbers connecting said piles, brace piles for said vertical piles having their upper ends in sliding engagement with the vertical piles, head timbers on the upper end of said brace piles 120 connecting said brace piles together, coiled springs vertically arranged on said head timbers, a plate on the upper end of said springs, rods secured to said vertical piles engaging said plate to compress said springs 125 by movement of the vertical piles, and a chain connected to the vertical piles and their associated brace piles.

6. In a wharf, a fore-structure comprising a series of vertical piles, timbers con- 130

necting said piles, brace piles for said vertical piles having their upper end in sliding engagement with the vertical piles and extending diagonally downwardly and 5 inwardly from their upper end, timbers connecting the upper ends of said brace piles, vertically disposed coiled springs on the timbers connecting said brace piles, a U-shaped member pivotally connected at its 10 closed end to the vertical pile and having its

open ends extending through said coiled springs, a plate on the upper end of said springs engaged by the open ends of the U member to compress said springs by movement of the vertical piles.

15

In testimony whereof, I have hereunto set my hand at Martinez, California, this 29th day of May, 1918.

WALTER HAGENBUCH.
